US00D863077S

(12) **United States Design Patent** (10) Patent No.: **US D863,077 S**
Shao (45) Date of Patent: **** Oct. 15, 2019**

(54) **METAL DETECTOR**

(71) Applicant: **Shenzhen Aukey E-Business Co., Ltd.**,
Shenzhen (CN)

(72) Inventor: **Zelong Shao**, Shenzhen (CN)

(73) Assignee: **Shenzhen Aukey E-Business Co., Ltd.**,
Shenzhen (CN)

(**) Term: **15 Years**

(21) Appl. No.: **29/660,570**

(22) Filed: **Aug. 21, 2018**

(51) LOC (12) Cl. **10-04**

(52) U.S. Cl.

USPC **D10/47**
